(57) **CLAIM**

The ornamental design for a multimedia terminal with transitional graphical user interface, as shown and described.

DESCRIPTION

FIG. 1 is a front view in a first image of a multimedia terminal with transitional graphical user interface having a dynamic image depending on tilt angle showing our new design; FIG. 2 is a perspective view in a second image thereof; FIG. 3 is another perspective view in a third image thereof; FIG. 4 is another perspective view in a fourth image thereof; FIG. 5 is another perspective view in a fifth image thereof; FIG. 6 is another perspective view in a sixth image thereof; FIG. 7 is another front view in a seventh image thereof; FIG. 8 is another front view in an eighth image thereof; FIG. 9 is another perspective view in a ninth image thereof; FIG. 10 is another perspective view in a tenth image thereof; FIG. 11 is another perspective view in an eleventh image thereof; FIG. 12 is another perspective view in a twelfth image thereof; FIG. 13 is another perspective view in a thirteenth image thereof; and, FIG. 14 is another front view in a fourteenth image thereof. The broken lines shown in the drawings depict environmental subject matter and form no part of the claimed design. The appearance of the transitional image sequentially transitions between the images shown in FIGS. 1-14. The process or period in which one image transitions to another image forms no part of the claimed design.
